UNITED STATES PATENT OFFICE.

RICHARD MONROE SILVA, OF BROOKLYN, NEW YORK.

HOSE-SUPPORTER.

1,377,031.

Specification of Letters Patent.

Patented May 3, 1921.

Application filed August 26, 1920. Serial No. 406,115.

To all whom it may concern:

Be it known that I, RICHARD M. SILVA, a citizen of the United States, and a resident of the city of New York, borough of Brooklyn, in the county of Kings and State of New York, have invented a new and Improved Hose-Supporter, of which the following is a full, clear, and exact description.

10 This invention relates to hose supporters, and is particularly adaptable for use with either stockings or socks.

An object of the invention is to provide a hose supporter in which substantially all 15 the pull or strain is taken off the hose, thereby eliminating the possibility of ripping and pulling threads in hose of silk or delicate texture.

Another object is to provide a supporter 20 in which by a simple adjustment the supporter is adaptable for use either in connection with a sock or in connection with a stocking.

A further object is to provide a supporter 25 connected with a body garment which tends to keep the body garment from slipping out of place.

Another object of the invention resides 30 in the particular arrangement and construction of parts which will be apparent from a consideration of the description and claims taken in connection with the drawings.

It is sometimes desirable where a body 35 garment is worn without being clasped too tightly to the body, to provide some means whereby this garment shall maintain its proper position. In addition, it is desirable to have a hose supporter, adapted for both socks and stockings, in which the strain or 40 pull of the connection between the hose and the body garment will be taken off the sock or stocking to eliminate the pulling out of threads in the hose.

To this end I provide a hose supporter 45 comprising a member which can be attached to the limb of the wearer some distance from the body garment and connect the body garment with this member, which is elastic, so as to create a steady tension on the body 50 garment to maintain it in a certain position with respect to the body. This body garment may be a corset, which, if not tightly fastened to the body, may slip upward. This connection prevents this action. 55 Adjustable hose-supporting tabs coöoperating with the above-mentioned means are pro-

vided with suitable fasteners and can be attached either to the member surrounding the limb or to the semi-elastic connection, adapting them for connection either with a sock 60 or a stocking. In the event that stockings are worn, the stockings are pulled up over the member gripping the limb to conceal the member.

The invention is illustrated in the drawings, of which—

Figure 1 shows the device applied to the limb of a wearer using socks;

Fig. 2 shows the device applied when a 70 stocking is being worn;

Fig. 3 is a side view of the connection between the body garment and the hose; and

Fig. 4 is a detail of the limb gripping member with the hose-supporting tabs attached thereto.

As shown in the drawings, the invention is used in connection with a body garment or corset 1. To a band of the corset, semi-elastic straps 2 of any suitable material extend downwardly along the limb of the 80 wearer. These straps are provided with the usual adjusting buckles 3 and with buttons 4 on the lower ends thereof, adapting them to be fastened to metallic loops 5 attached to the upper edge of a band 6. This band is 85 made of any suitable fabric and may be somewhat elastic. It is adapted to be adjusted by means of a buckle 7 around the limb of the wearer, preferably just below the knee. After adjusting this gripping 90 member or band 6 in this position, and suitably adjusting the straps 2, a definite tension in these straps will tend to maintain a constant pull on the corset 1, which is sometimes desirable.

This band 6 is provided around its face with a plurality of members 8 which form part of a means for attaching to the band 6 a hose-supporting tab 10 in which is co-operating fastening means 9. These fastening devices 8 and 9 may be the usual snap fasteners or any suitable form of fasteners. The lower end of the tab 10 is provided with the usual loop and button hose fastening device 11. The straps 2, intermediate 105 their length between the band 6 and the corset 1, are also provided with similar fasteners 8' to which the tabs 10' can be attached.

In Fig. 1 the tabs 10 are shown depending 110 from the strap 6 to engage with a sock 12; whereas in Fig. 2 the tabs 10' are fastened

to the fasteners 8' and depend therefrom to connect with a stocking 13. When a stocking is worn, the band 6 and the lower portion of the straps 2 are hidden by the fabric 5 of the stocking. It will be observed that in either case the strain of any pull between the corset through the straps 2 will be taken and borne by the band 6, thus relieving the tabs 10 of any pull either on the sock or 10 stocking and thereby eliminating the tendency to pull the threads of the same.

What I claim is:

1. A hose supporter attached to a body garment, comprising a band attached to the 15 limb of the wearer some distance from the garment, an elastic connection between the band and the garment, hose-supporting means, means on said band, and means on said elastic connection intermediate its 20 length between the band and said body garment, both of said means adapted to co-operate with said supporting means to support short or long hose, respectively.

2. A hose supporter attached to a body

garment, comprising a semi-elastic band 25 attached to a limb of the wearer below the knee, an adjustable elastic connection between the band and the body garment, hose-supporting tabs, means on said band, and means on said elastic connection intermediate 30 its length between the band and said body garment, both of said means adapted to co-operate with said tabs to support short and long hose, respectively.

3. A hose supporter attached to a body 35 garment, comprising a band encircling a limb of the wearer below the knee, and an elastic connection between the band and the body garment adapted to absorb all tension therebetween, a hose-supporting tab adapted to be attached to said band, and means on said elastic connection adapted to receive 40 said tab to support longer hose, said band adapted to lie beneath the hose when the hose extends above the band and connects 45 with the tab on the elastic connection.

RICHARD MONROE SILVA.
